DECORATIVE BUILDING BLOCK

Martin E. Veale, Sr., Tulsa, Okla.

Application December 18, 1956, Serial No. 44,245

Term of patent 14 years

(Cl. D18—2)

Fig. 1

Fig. 2

Fig. 3

Figure 1 is a perspective view of a decorative building block showing my new design;

Figure 2 is a side elevational view thereof taken from the side opposite that shown in Figure 1; and

Figure 3 is an end elevational view of the same.

I claim:

The ornamental design for a decorative building block, as shown.
